POT HOLDER RACK

Helen Richards, Chicago, Ill.

Application September 3, 1954, Serial No. 32,163

Term of patent 3½ years

(Cl. D44—29)

Fig. 2

Fig. 1 is a front elevational view of a pot holder rack showing my new design;

Fig. 2 is a top view thereof; and

Fig. 3 is a bottom view thereof.

I claim:

The ornamental design for a pot holder rack, substantially as shown.
